CLAIM

The ornamental design for a display screen or portion thereof with a group of graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

The FIGURE is a front view of a display screen or portion thereof with a group of graphical user interface showing the claimed design.

The broken lines in the figures show a display screen or portion thereof, and form no part of the claimed design.

The group of graphical user interface of the FIGURE is arranged on the drawing sheet for the convenience of illustration, and the placement of each element relative to another, or to the drawing sheet, forms no part of the claimed design. The bracket shown in the FIGURE forms no part of the claimed design.
